UNITED STATES PATENT OFFICE.

DENNIS L. JOHNSON, OF COOKS MILLS, ILLINOIS, ASSIGNOR OF ONE-HALF
TO DAVID F. HOOTS, OF MATTOON, ILLINOIS.

EAVES-TROUGH.

No. 828,291.

Specification of Letters Patent.

Patented Aug. 7, 1906.

Application filed October 30, 1905. Serial No. 285,056.

To all whom it may concern.

Be it known that I, DENNIS L. JOHNSON, a citizen of the United States, residing at Cooks Mills, in the county of Coles and State of Illinois, have invented certain new and useful Improvements in Eaves-Troughs, of which the following is a specification.

My invention has reference to eaves-troughs, and more particularly to screens for preventing the collection of leaves and other trash therein; and it contemplates the provision of a simple, strong, and durable screen and one adapted to be applied and connected to a roof and an eaves-trough with great facility and also adapted to tie the trough to the roof with a view of strengthening the connection of the former to the latter.

Other advantageous features peculiar to my invention will be fully understood from the following description when the same is considered in connection with the accompanying drawings, forming part of this specification, in which—

Figure 1 is a transverse section illustrating one arrangement of my improved screen relative to a roof and an eaves-trough. Fig. 2 is a top plan view of the screen *per se* removed. Fig. 3 is an enlarged transverse section taken in the plane indicated by the line 3 3 of Fig. 2 looking in the direction indicated by arrow; and Fig. 4 is a view similar to Fig. 1, illustrating a different arrangement, hereinafter referred to, of my novel screen relative to a roof and an eaves-trough.

Referring by letter to said drawings, and more particularly to Figs. 1 to 3 thereof, A is a portion of a side wall of a building. B is the shingle roof thereof, and C is an eaves-trough. All of these parts may be and preferably are of the ordinary well-known construction, the trough C being secured to the facier or crown-molding or cornice of the building and arranged to receive water, &c., from the shingle roof, which is sharply pitched, as illustrated.

D is my novel screen as a whole. The said screen comprises an open frame, of comparatively large-caliber galvanized-steel wire, having parallel side stretches a and also having end stretches b, longitudinal mesh-wires c of small caliber and soft galvanized metal extending between and connected to the end stretches b of the open frame D and arranged about the proportional distance illustrated apart, and cross mesh-wires d of similar

metal extending between and connected to the side stretches a of the frame and interlaced with the longitudinal wires c, as shown. Some of the cross-wires d, preferably those 60 adjacent to the ends of the open frame and certain of those arranged at intervals in the length of the screen, are extended beyond one longitudinal side of the screen-frame, as indicated by E, for a purpose presently described.

In case the eaves-trough is secured to the facier or crown-molding or cornice of a house my novel screen is applied in the manner shown in Fig. 1—that is to say, the screen is 70 arranged with one longitudinal side of its frame bearing on the shingle roof B and the other longitudinal side of said frame resting on the bead e, usually provided at the outer edge of the eaves-trough. With the screen 75 thus arranged the inner side of the screen-frame is connected by staples f to the roof B, while the tongues E, afforded by the extension of the cross mesh-wires beyond one side of the screen-frame, are bent down and under 80 the bead e, as shown in said Fig. 1. By virtue of this latter it will be observed that the screen is expeditiously and securely fastened at its outer edge to the outer edge of the trough; also, that the outer edge of the screen 85 is held down tight on the bead e of the trough, and this without liability of the screen being broken or its mesh opened. From this it follows that there is no liability of openings 90 being formed between the screen and the trough through which trash can enter the trough, and it will also be observed that in addition to effectually preventing trash from entering and settling in the eaves-trough the screen assists materially in the connection of 95 the eaves-trough to the building.

In lieu of connecting one side of the screen-frame to the shingle roof through the medium of staples, as shown in Fig. 1 and before described, the side of the screen-frame may 100 be secured under the lower shingles of the roof B, as shown in Fig. 4. When this arrangement is resorted to, the eaves-trough may be connected to the facier or crown-molding or cornice after the manner shown 105 or else may be connected to the extended portion of the shingle roof.

In practice I contemplate manufacturing my novel screens in sections of various lengths and widths and with ends of different 110 angles to fit gutters of different makes and sizes.

It will be gathered from the foregoing that an important advantage peculiar to my novel screen is that the said screen is adapted to be expeditiously and securely applied without 5 the necessity of cutting or otherwise weakening the screen, diminishing the wearing qualities thereof.

Having thus described my invention, what I claim, and desire to secure by Letters Patent, is—

The combination with the roof of a building, and an eaves-trough arranged to receive from the roof and having a bead on its outer edge; of a screen comprising an open frame, 15 of large-caliber wire, having sides and ends; one of said sides resting on the bead of the

eaves-trough, and the other being connected to the roof, longitudinal mesh-wires, of comparatively small caliber, connected to and extending between the ends of the frame, and 20 cross-wires, of the same caliber as the longitudinal wires, interlaced with said longitudinal wires and extending between and connected to the frame sides and also extending beyond the outer frame side and bent under 25 the bead on the eaves-trough.

In testimony whereof I affix my signature in presence of two witnesses.

DENNIS L. JOHNSON.
